UNITED STATES PATENT OFFICE.

SAMUEL E. KELLOGG, OF JOHNSTOWN, PENNSYLVANIA.

TYPO-PHOTO FILM PROCESS.

Application filed January 3, 1927. Serial No. 158,725.

This invention relates to photography and more particularly to a novel method of treating films or negatives, so that when the pictures are printed therefrom titles and the like will be printed directly thereon.

The primary object of the present invention is the provision of a novel process of treating a film or negative, so as to cause suitable indicia to be printed directly thereon, whereby when pictures are printed from the negative the picture will bear the indicia thereon, thereby eliminating the necessity of marking a film by hand or attaching a printed or typewritten label on the finished photograph, the process rendering the negative particularly adaptable for advertising purposes.

A further object of the invention is the provision of a novel process of marking a title, advertising matter or the like on a film, which comprehends first the setting of type on a platen press for printing upon the lightest portion of the film or negative to form the darkest portion of the picture, placing a sheet on the tympan of the press for receiving an impression from the type, then placing the film smooth side up upon the sheet and then placing a couple of sheets of paper on top of the film to protect the same and to secure a heavy impression and then making the impression on the whole, whereby the film will be found to be perfectly printed in offset on the film side.

A still further object of the invention is to provide a novel process of printing films of the above character, which will be simple and easy to carry out and which will allow the pictures to be readily made therefrom bearing suitable indicia thereon.

With these and other objects in view, the invention consists in the novel arrangement, as will be hereinafter more fully described, claimed, and illustrated in the accompanying drawings, in which drawings:

Figure 1 shows a fragmentary top plan view of the tympan of a press with the gage pins in correct position thereon and the initial sheet with the indicia printed thereon.

Figure 2 is a similar view with the film or negative to be printed, placed on top of the initial sheet, the film being partly broken away to illustrate the fact that the same covers the entire surface of the initial sheet.

Figure 3 is a longitudinal section through the tympan of the press with the initial

sheet in place, the film thereon and a pair of impression sheets placed on top of the film with the type printing on the impression sheets to make the impression thereon.

Figure 4 is an elevation of the completed film after the same has been printed, showing the smooth side thereof.

Figure 5 is a reverse view of the film showing the film side thereof with the impression thereon, and

Figure 6 is an elevation of a picture made from the film.

Referring to the drawings in detail, wherein similar reference characters designate corresponding parts throughout the several views, the letter A generally indicates a fragment of a platen press which is of the conventional construction and which includes the usual platen or tympan 10, and the form 11. The letter B indicates a negative or film 15 to be treated in accordance with the process.

In accordance with this process the printer proceeds to make the job ready in the usual way on the press A and he must use new sharp type in order to get a perfect impression. It is essential that the matter to be printed is arranged in the form in such a manner as to align with the lightest portion of the film or negative B and the gage pins 12 are placed in position in the usual way. An impression is now made on the tympan and the film is placed thereover to see if the matter to be printed properly comes on the film and his gage pins are set right.

A sheet of paper 13 of cardboard or the like is placed on the platen in engagement with the gage pins 12 and a perfect impression is made thereon. This constitutes the first step of the process. The film is now placed against the gage pins 12 on top of the sheet 13 with the smooth side up and the emulsion surface underneath. This constitutes the second step of the process. The third step consists in placing two or more sheets of paper 14 on top of the film to protect the same and to insure a heavy enough impression thereon. The printer now makes an impression on the whole and removes the film. This forms a perfectly printed face in offset on the emulsion side of the negative as clearly shown in Figure 5 of the drawings. Thus when a picture 15 is made from the film the indicia 16 will be printed on the darkened portion thereof as shown.

Cuts, engravings and the like can be made

from a film with the printing thereon in the usual way.

In case pictures are to be taken which do not have a dark background, which is essential for the printing process the film is treated before the picture is taken so as to insure light spaces thereon.

From the foregoing description, it can be seen that a novel process has been provided for printing suitable indicia directly on film negatives, so that when pictures are printed from the negatives the same will have the desired printed matter thereon.

Changes in details may be made without departing from the spirit or the scope of this invention, but what I claim as new is:

1. The method of printing indicia on a negative, consisting in setting up the indicia

in type, in making an impression of the indicia, in placing the negative on the impression, in placing a protecting member on the negative, and in applying pressure to the protecting member by means of the indicia type and with the type arranged in registration with the impression. 20

2. The method of printing indicia on a negative, consisting in setting up the indicia in type, in making an impression of the indicia, in placing the negative with the emulsion side next to the impression, in placing a protecting member against the negative, and in applying pressure to the protecting member by means of the indicia type and with the type arranged in registration with the indicia. 25

In testimony whereof I affix my signature.

SAMUEL E. KELLOGG.
